UNITED STATES PATENT OFFICE

GUSTAV EGLOFF AND HARRY P. BENNER, OF CHICAGO, ILLINOIS, ASSIGNEES TO
UNIVERSAL OIL PRODUCTS COMPANY, OF CHICAGO, ILLINOIS, A CORPORATION OF
SOUTH DAKOTA

PROCESS FOR TREATING PETROLEUM OIL

Original application filed October 21, 1920, Serial No. 418,567. Divided and this application filed July 17, 1924. Serial No. 726,439. Renewed August 14, 1930.

This application is a division of an application filed by us on October 21st, 1920, as Serial No. 418,567.

This invention relates to a process for treating petroleum oil, and refers more particularly to a process adapted for the conversion of relatively heavier into lighter hydrocarbons by the so-called cracking operation. By means of the present invention, a very considerable increase in output of gasoline or like hydrocarbons can be produced by the cracking process, and at the same time a higher quality is obtained, due to certain scrubbing actions hereinafter referred to.

15 In the drawing:

Fig. 1 is a view, partly in side elevation and partly in vertical section, of our improved apparatus.

20 Fig. 2 is an enlarged sectional view taken on lines A—A of Fig. 1.

Referring in detail to the drawing, 1 designates the furnace, 2 the burner, 3 the fire box, 4 the bridge walls and 5 the flue tunnel leading to the stack (not shown). Mounted in 25 the furnace is a still 6 in the present instance of the shell or cylindrical type, having man-hole plate 7 and equipped with a liquid draw-off 8, controlled by valve 9. This still also has a vapor outlet 10, controlled by a throttle 30 valve 11. The upper end of this vapor pipe 10 is provided with a right angled vertical extension 12, which projects as shown clearly, into a combined scrubber and cracker 13. This member 13 which may take the form of a 35 cylindrical drum, is suitably supported on standards or brickwork 14 and is provided with manhole plate 15 and liquid level gauge 16. It also has a residue drawoff pipe 17 having throttle valve 18. Within the drum 40 13 is a longitudinally extending cap or baffle 19, which as shown clearly in Fig. 2 projects above the upper end of the extension 12, the arrangement being such as to compel the vapors which pass out of the pipe 12 to pass down through the liquid contents of the drum under the lower parts 20 of the baffle. Preferably the drum 13 is maintained with liquid 45 at the level shown by the dotted line α . This liquid is introduced and maintained at a pre-determined level through the pipe 21 having

throttle valve 22, which pipe may lead to a suitable oil supply pump.

The vapors pass out of the drum through the vapor outlet pipe 23 having throttle valve 24, which pipe projects as shown into 55 the lower end of a dephlegmator 25. The upper end of the pipe 23 is provided with the spaced cap member 26 to prevent reflux condensate from falling back into the pipe. This reflux condensate instead, is drawn off 60 through the pipe 27, having throttle valve 28, the pipe normally leading back to the main feed line 29 for the still 6. This feed line 29 connects to a feed pump 30 leading to any suitable source of raw oil supply. Throttle 65 valves 31 and 32 are connected to the discharge and inlet sides of the pump 30 respectively. If desired, the reflux condensate may be drawn off through a branch pipe 33 having 70 throttle valve 34.

The dephlegmator has a series of alternately disposed baffles 35 and at its upper end is connected to the vapor pipe 36 having throttle valve 37, which pipe leads to a condenser coil 38 seated in condenser box 39. 75 The lower end of coil 38 is connected by pipe 40, regulated by throttle valve 41, to the upper end of receiver 42. This receiver 42 is provided with liquid level gauge 43 and pressure gauge 44. It also has liquid drawoff 80 pipe 45 having throttle valve 46 and gas outlet pipe 47 regulated by throttle valve 48.

The process may be operated as follows: Fuel oil from the Mid-Continent crude petroleum, may be charged into the still, either 85 continuously or intermittently, and there heated to a temperature of say 750° F., the vapors may be permitted to pass freely through the pipe 10 into the drum 13. This drum 13 contains a liquid such as Mid-Continent gas oil maintained at the level shown by the dotted line α , through regulation of the valve 22, and the vapors as they pass out of the upper end of the pipe 12 are compelled by means of the member 19 to pass 90 down through the liquid in the tank 13 before they can pass freely through the pipe 23 into the dephlegmator. In their passage through the gas oil, these vapors are scrubbed 95 and there is a tendency to free them from 100

their heaviest or undesirable constituents. At the same time, the heat of the vapors is such that at the pressure maintained in the system, a certain percentage of the gas oil 5 may be cracked and the lighter constituents thereof pass out through the vapor outlet 23. The vapors which are condensed in the dephlegmator 25 may be freely returned through the pipe 27 continuously back to the 10 feed line 29. In such case, the valve 28 is opened and the valve 34 closed. The vapors which are not condensed in the dephlegmator pass to the condenser 38 and thence to the receiver 42. A pressure of 125 pounds may 15 be maintained on the entire system and 50% to 60% of the charge in the still 6 converted into pressure distillate of say, 52 Baumé gravity. In addition, a certain percentage of the gas oil will be cracked and the light 20 constituents thereof removed.

As a modified method of carrying out the process, the gas oil may be introduced in heated condition, say at a temperature of 400 degrees F., into the chamber 13, which 25 if advantageous, may be insulated. This gas oil will therefore be more readily cracked than if cold.

As a still further modification of the process, differential pressures may be maintained, as for example, 200 pounds on the 30 still, 150 pounds on the chamber 13, 100 pounds on the dephlegmator 25, 75 pounds on the condenser coil 38, 50 pounds on the receiver 42. In such cases, the reflux condensate may be more readily drawn out 35 through the branch 33 by closing the valve 28 and suitably regulating the valve 34.

We claim as our invention:

1. A process for cracking hydrocarbon oils, 40 consisting in distilling the charging oil at a cracking temperature under superatmospheric pressure, in passing the generated vapors to a combined scrubbing and cracking vessel, in maintaining a predetermined supply of a second oil in said vessel, in compelling 45 the vapors evolved from the charging oil undergoing pressure distillation to pass first downwardly and thence upwardly through the supply of said second oil in said 50 vessel before escaping therefrom to simultaneously scrub such vapors and crack some fractions of the oil in said vessel, in discharging scrubbed vapors evolved from said 55 charging oil, commingled with vapors released from said second oil, from said vessel to a dephlegmator, wherein the insufficiently cracked fractions are condensed, 60 forming reflux condensate, in retreating the reflux condensate by uniting the same with the charging oil undergoing treatment in the process, and in condensing the dephlegmated 65 vapors and collecting the resulting distillate.

2. A process for simultaneously treating 66 separate oils, to produce therefrom a common product of lower boiling point than

either of the oils treated, which consists in maintaining a bulk supply of one of said oils under cracking conditions of heat and pressure, in maintaining the other oil in a separate body, in preventing commingling of the liquid oil maintained in said bulk supply and in said body, in passing vapors evolved from the oil maintained in said bulk supply, prior to reflux condensation, through said body of the other oil, to cause vaporization of substantial quantities of such body of oil, in subjecting the commingled vapors evolved from the bulk supply of oil and released from said body of oil to reflux condensation, to separate insufficiently cracked fractions 70 therefrom, in returning such insufficiently cracked fractions, in the form of reflux condensate, to said bulk supply of oil, and in continuously admitting additional charging oil from independent sources to said bulk 75 supply and to said body of oil, while maintaining a superatmospheric pressure on the oil undergoing treatment in the process.

GUSTAV EGLOFF.
